(Cl. D34—15)

To all whom it may concern:

Be it known that we, Sidney Wasserman and Allen M. Sterns, citizens of the United States, residing at Detroit, in the county of Wayne and State of Michigan, have invented a new, original, and ornamental Design for a Toy Gun, of which the following is a specification, reference being had to the accompanying drawings, forming part thereof.

Figure 1 is a perspective view of a toy gun, showing our new design;

Figure 2 is a side elevation thereof part of the front sight being broken away for convenience of illustration, and

Figure 3 is an end view.

We claim:

The ornamental design for a toy gun, as shown.

SIDNEY WASSERMAN.
ALLEN M. STERNS.
